PRINTING OR OTHER MACHINE

Walter C. Scott, Plainfield, N. J.

Application June 11, 1936, Serial No. 84,678

20 Claims.

(Cl. 270—5)

This invention relates generally to printing or other machines and has more particularly reference to a system of speed control associated therewith. The main object and feature of the invention is to coordinate the speed relationship of separately driven devices or units, and to do so by simple and effective means.

In the accompanying drawings the invention is disclosed in one form in which:

10 Fig. 1 is a more or less diagrammatic view, partly in section;

Fig. 2 is a longitudinal sectional view of one of the control mechanisms; and

15 Fig. 3 is a transverse sectional view substantially on the plane of line 3—3 of Fig. 2.

Referring to Fig. 1, A and B indicate a plurality of devices or units. For the purpose of arbitrarily distinguishing between these devices, A will be referred to as the "primary" device, and 20 B as "secondary" devices. In the present case the plurality of devices or units is greater than two, and consist of the printing and folding units of a printing machine, the folding unit A of which constitutes here the "primary" device and the printing and perfecting units or couples B of which constitute here the "secondary" devices. It is unnecessary to describe the operation of a machine of this character except to say that webs are led to the printing couples and are thereafter 25 associated and folded in the folding mechanism known as a "former folder".

So far as certain features of the invention are concerned, the speed control mechanism may take many forms but, preferably, the control mechanism disclosed and claimed in my application Ser. No. 60,423, filed January 23, 1936, will be utilized because, owing to its simplicity and effectiveness, it constitutes an almost ideal mechanism for use in connection with a printing or other machine where the speed of a plurality of units greater than two is to be coordinated. As a matter of convenience, therefore, and for the purpose of bringing out certain features of the invention, the particular control mechanism here employed will now be described, it being understood that the invention in all its aspects is not limited to the control mechanism so described.

The control mechanism is indicated by O and it will be noted that there is a separate control mechanism associated with each of the secondary units or devices and, as will presently be explained, all the control mechanisms are associated with the primary device or unit. Each control mechanism consists of two control members X and Y arranged side by side and inde-

pendently rotatable in the same direction on a supporting shaft I. At least one of these control members, here Y, is movable sidewise or axially and is normally urged toward the other member by a spring 2. Control member X is provided with a series of arcuate or segmental grooves 3 of taper formation, that is, one end 4 is deeper than the other end 5. Control member Y is provided with a continuous surface 6. Balls 7 are located in grooves 3 of member X 10 and engage continuous surface 6 of member Y. It will be understood that, when balls 7 are in deep end 4 of the grooves, spring 2 will bring members X and Y close together but that, if the balls are in shallow end 5 of the grooves, 15 the camming action of said balls will force members X and Y apart against the tension of spring 2. The position of the balls in the grooves is controlled by the relative speed of control members X and Y, and it will be understood that, so long as the speed of member X is greater than or equal to that of member Y, the balls will remain in the deep end of the grooves but that, when the speed of member Y exceeds that of member X, the balls will move toward the shallow end of the grooves and force members X and Y apart. A control element Z is pivotally supported at 8 and is normally urged into engagement with member Y by spring 9, and it will be understood that the sliding movement 20 of Y effects or permits a corresponding movement of control element Z, which movement can be utilized to govern a clutch, a rheostat, cone pulleys and belts or what-not as fully explained in my said application Ser. No. 60,423 above referred to.

As disclosed in my said application Ser. No. 60,423, the several devices or units can be separately driven from a single prime mover by any suitable means through speed change mechanisms such as the well-known Reeves drive which could then be under the control of control elements Z. In the present disclosure the several units are not only separately driven but are driven from independent motors. As seen 25 in Fig. 1, motor C drives folder A by means of suitable transmission means indicated at 10, and motors D drive printing units B by means of suitable transmission means indicated at 11, the cylinders of each printing and perfecting couple 30 being intergeared in the usual way. Folder A drives a shaft 12, extending along the different units, by suitable transmission means 13, and control member X of each control mechanism is driven from shaft 12 by suitable transmission 35

means 14. Control member Y of each control mechanism is driven from the printing and perfecting couple with which it is associated by suitable transmission means 15. All the motors 5 are connected in parallel to leads L, and motor C can have its speed controlled by a suitable means such as rheostat R. The circuit of each of motors D is here controlled by a rheostat R' of which control element Z forms the movable member. The desired relative speed is established by suitable gear ratios. In some printing machines the folder runs at say half the speed of the printing units, but in the present instance both the folder and the printing units run at the 10 same speed, and the gear ratio, accordingly, is such that, when the folder and a printing unit run at equal speed, control members X and Y also run at equal speed. If it were desired to run the folder say at one-half the speed of the printing unit, the gear ratio would be such that control members X and Y would run at equal speed when the folder runs at half the speed of the printing unit.

It will now be understood that, when power is supplied to the machine, motors D will continue to accelerate so long as control member Y does not exceed the speed of control member X but that, so soon as it does, control element Z will cut in more resistance to thereby decelerate the 25 speed of motor D, and in this connection it may be remarked that the amplitude of movement of control element Z may be such that power to motor D is cut off altogether when the speed of control element Y exceeds that of control element X, thereby causing motor D to run due to its own momentum until it has decelerated sufficiently, after which power is again applied.

It may also be pointed out that the circuit of each motor D can be supplied with a manually operated controlling mechanism such as rheostat R2.

Considering now the system as a whole, it will be seen that Fig. 1 shows a plurality of separately driven devices or units greater than two and that the speed of a number of these devices 45 or units, such as B, is individually and simultaneously controlled with respect to the speed of a single device or unit, such as A. It will further be seen that in carrying out the method of the above system there is employed a plurality 50 of control mechanisms, such as O which are responsive to the speed of a primary device, such as A, and individually and simultaneously responsive to the speed of the secondary devices, such as B, to individually govern the speed of devices B. In analyzing the system still more 55 in detail, it will be seen that there is employed a plurality of control members, such as X and Y, which are arranged in pairs, the number of pairs being equal to the number of devices B. 60 and that means are employed to drive one control member of each pair at a speed proportional to (not necessarily equal to) that of device A, together with means to drive the other control members of said pairs at speeds proportional to (not necessarily equal to) those of devices B; and that means, such as elements Z, which are responsive to variations in speed 65 between the control members X and Y of a pair, control the speed of that device B which drives the member Y of that pair.

It will also be seen that the system contemplates the use of a shaft, as 12 which is driven from a unit, as A, and a plurality of control 75 mechanisms O for individually governing the

speed of units B, each of said units B being governed by a different control mechanism O, and that there are means to render all of the control mechanisms O responsive to the speed of shaft 12 and each control mechanism responsive to the speed of the unit B which it governs. 5

In the foregoing description it has been assumed that the direction of rotation of members X and Y is as indicated by the arrow in Fig. 3; 10 that is, with shallow end 5 of slots 3 leading and deep end 4 trailing. It will, however, be understood that the direction of rotation could be the reverse of that indicated, in which event members X and Y would be separated so long 15 as the speed of X exceeds or is equal to that of Y but that, when the speed of Y exceeds that of X, the two members would approach each other. In these circumstances, the effect of the movement of element Z should be correspondingly 20 altered.

I claim:

1. The method of obtaining a desired speed relationship of a plurality of separately driven devices greater than two which consists in independently but simultaneously controlling the speed of a plurality of such devices with respect to the speed of a single device without affecting the speed of the single device by the speed of the plurality of devices. 30

2. A system of speed control including: a primary device; a plurality of secondary devices driven separately from each other as well as separately from the primary device; and a plurality of control mechanisms responsive to the speed of the primary device and individually and simultaneously responsive to the speed of the secondary devices to independently govern the speed of the secondary devices but not that of the primary device. 40

3. A system of speed control including: a primary device; a plurality of secondary devices driven separately from each other as well as separately from the primary device; a plurality of control members arranged in pairs, the number of pairs being equal to the number of secondary devices; means to drive one control member of each pair at a speed proportional to that of the primary device; means to drive the other control members of said pairs at speeds proportional to those of the secondary devices, each secondary device driving one control member; and means responsive to variations in speed of the control members of a pair to control the speed of that secondary device which drives a 55 member of that pair.

4. A system of speed control including: a plurality greater than two of separately driven units; a shaft; means to drive said shaft from one of said units; a plurality of control mechanisms for individually governing the speed of the remaining units, each of said remaining units being governed by a different control mechanism; means to render all of said control mechanisms responsive to the speed of the shaft; and means independent of said shaft to render each control mechanism responsive to the speed of the unit which it governs. 60

5. A system of speed control including: a plurality greater than two of separately driven units for printing and folding material; a shaft; means to drive said shaft from one of said units; a plurality of control mechanisms for individually governing the speed of the remaining units, each of said remaining units being associated 70

- with and governed by a different control mechanism; means to render all of said control mechanisms responsive to the speed of the shaft; and means independent of said shaft to render each control mechanism responsive to the speed of the unit with which it is associated and which it governs.
6. A system of speed control including: a plurality of printing units and a folding unit, separately driven; a shaft; means to drive said shaft from the folding unit; a plurality of control mechanisms for individually governing the speed of the printing units, each of said printing units being governed by a different control mechanism;
- 10 means to render all of said control mechanisms responsive to the speed of the shaft; and means independent of said shaft to render each control mechanism responsive to the speed of the printing unit which is governed.
- 15 7. The combination with a plurality of separately driven units, of a plurality of control mechanisms all of which are responsive to the speed of one of said units and each of which is only responsive to the speed of a different unit of the remaining ones; and means to control the speed of said remaining units from said control mechanisms, each of said remaining units being governed by a different control mechanism from that which governs any of the other remaining units.
- 20 8. The combination with a plurality of separately driven units for printing and folding material, of a plurality of control mechanisms all of which are responsive to the speed of one of said units and each of which is only responsive to the speed of a different unit of the remaining ones; and means to control the speed of said remaining units from said control mechanisms, each of said remaining units being governed by a different control mechanism from that which governs any of the other remaining units.
- 25 9. The combination with a plurality of printing units and a folding unit, separately driven, of a plurality of control mechanisms all of which are responsive to the speed of the folding unit and each of which is only responsive to the speed of a different printing unit; and means to control the speed of the printing units from said control mechanisms, each of said printing units being governed by a different control mechanism from that which governs any of the other printing units.
- 30 10. The combination with a plurality, greater than two, of separately driven units for printing and folding material, of means responsive to the speed of one unit for independently controlling the speed of the remaining units without affecting the speed of said one unit by the speed of the remaining units.
- 35 11. The combination with a plurality, greater than two, of separately driven units for printing and folding material, of means responsive to the speed of one unit for simultaneously but independently controlling the speed of the remaining units without affecting the speed of said one unit by the speed of the remaining units.
- 40 12. The combination with a plurality of printing units and a folding unit, separately driven, of means responsive to the speed of the folding unit for independently controlling the speed of the printing units without affecting the speed of the folding unit.
- 45 13. The combination with a plurality of printing units and a folding unit, separately driven, of means responsive to the speed of the folding unit for simultaneously but independently controlling the speed of the printing units without affecting the speed of the folding unit.
- 50 14. The combination with a plurality of units for printing and folding material, of a motor for each unit, and means to control, by the speed of one motor, the speed of the remaining motors without controlling the speed of the one motor by the speed of the remaining motors.
- 55 15. The combination with a plurality of operating units greater than two, of a motor for each unit, and means to control, by the speed of the motor of one unit, the speed of the motors of the remaining units without controlling the speed of the motor of the one unit by the speed of the motors of the remaining units.
- 60 16. A method of obtaining a desired speed relationship between a primary device and a plurality of secondary devices in which all of the aforesaid devices are separately driven and in which the secondary devices are unresponsive to the speed of one another but are independently and simultaneously responsive to the speed of the primary device, and in which the primary device is not responsive to the speed of the secondary devices.
- 65 17. The method of obtaining a desired speed relationship of a plurality of separately driven devices greater than two which consists in independently but simultaneously controlling, with respect to the speed of one of said devices, the speed of the remaining devices, the speed of said one device being uncontrolled by the speed of said remaining devices.
- 70 18. A method of obtaining a desired speed relationship between a plurality of separately driven units greater than two in which the speed of a plurality of subservient units is independently and simultaneously controlled by the speed of a master unit and in which the speed of the master unit is uncontrolled by the speed of the subservient units.
- 75 19. A method of obtaining a desired speed relationship between the separately driven units of a printing machine in which the speed of a plurality of subservient units is independently and simultaneously controlled by the speed of a master unit and in which the speed of the master unit is uncontrolled by the speed of the subservient units.
- 80 20. A system of speed control including: a primary device; a plurality of secondary devices driven separately from each other as well as separately from the primary device; a plurality of control mechanisms, one associated with each secondary device, each control mechanism including two rotatable control members that rotate independently of each other at all times; means to drive one control member of each control mechanism proportional to the speed of the primary device; means to drive the other of said control members of each control mechanism proportional to the speed of that secondary device with which a particular control mechanism is associated; and means responsive to variations in speed of the members of a control mechanism to control the speed of that secondary device with which said control mechanism is associated.

WALTER C. SCOTT.
